UNITED STATES PATENT OFFICE.

FRANCISCO R. YCASIANO, OF CALOOCAN, PHILIPPINE ISLANDS.

SUPERHEATER UNIT.

Application filed September 16, 1925. Serial No. 56,728.

This invention relates to superheater units for boilers and has for its principal object to provide a simple and efficient means for supporting a plurality of superheater elements in the flue pipe.

One of the important objects of the invention is to provide a superheater unit of the above mentioned character, wherein an autogenous weld is employed for supporting the 10 superheater elements in spaced relation.

A further object is to provide a superheater of the above mentioned character with means of supporting in spaced relation the tube elements, which is simple in construction, inexpensive, strong and durable, and further well adapted for the purpose for which it is designated.

Other objects and advantages of this invention will become apparent during the 20 course of the following description.

In the accompanying drawing, forming a part of this specification, and in which like numerals designate like parts throughout the same:

25 Figure 1 is a longitudinal sectional view through a flue, showing the manner in which a set of superheater elements is supported in spaced relation therein.

Figure 2 is a transverse sectional view, 30 taken approximately on line 2—2 of Figure 1, and

Figure 3 is a similar section taken substantially on the line 3—3 of Figure 1.

In the drawing, wherein for the purpose 35 of illustration is shown the preferred embodiment of my invention, the numeral 1 designates generally the superheater unit, the same comprising the superheater flue 2, in which is arranged the plurality of longitudinally extending superheater tubes 3. For the purposes of supporting the tubes in longitudinal spaced relation, a cross bar, such as is shown at 4 is disposed between the upper and lower pairs of superheater 40 tubes at spaced intervals throughout the length thereof. The superheater tubes are autogenously welded to the bar 4, as illustrated at 5.

The alternate cross bars 4 are provided with the extensions 6 at the ends thereof, 50 and the extensions are disposed downwardly around the lower pair of superheater tubes, so that the free ends of the extensions will engage the inner wall of the flue 2, whereby the superheater tubes are spaced from the 55 inner walls of the flue. The extensions 6 are autogenously welded to the lower pair of tubes, as illustrated at 7.

It will thus be seen from the foregoing description that a superheater unit has been 60 provided, wherein the superheater tubes are supported in longitudinal spaced relation with respect to each other within the flue, and are further supported in spaced relation with respect to the inner wall of the 65 flue.

While I have shown the preferred embodiment of my invention, it is to be understood that various changes in the size, shape and arrangement of parts may be resorted to, 70 without departing from the spirit of the invention or the scope of the appended claim.

Having thus described my invention, what I claim is:

In a superheater unit, a flue, a plurality of longitudinally extending superheater tubes arranged therein, flat cross bars interposed between the tubes and being autogenously welded to said tubes for supporting the same in longitudinal spaced relation with respect to each other, the alternate bars being of greater length than the other bars, said longer bars each having its respective ends disposed downwardly adjacent the underlying tube, and autogenously welded thereto, the free ends of the longer bars being adapted to engage the inner wall of the flue for supporting the superheater tubes in spaced relation with respect to the inner wall of the flue.

In testimony whereof I affix my signature.

FRANCISCO R. YCASIANO.
